CLAIM

The ornamental design for a coin sorting bank, as shown and described.

DESCRIPTION

FIG. 1 is a top perspective view of a coin sorting bank showing my new design, the undisclosed bottom forms no part of the claimed design;

FIG. 2 is a front elevation view thereof;

FIG. 3 is a left side elevational view, the right side is a mirror image thereof;

FIG. 4 is a rear elevation view thereof;

FIG. 5 is a top plan view thereof; and,

FIG. 6 is a top plan view thereof with the top portion removed for clarity.

The broken line showing of the features in all views is for illustrative purposes only and forms no part of the claimed design.
